UNITED STATES PATENT OFFICE.

BARTON L. PECK, OF DETROIT, MICHIGAN.

MOTOR-VEHICLE.

SPECIFICATION forming part of Letters Patent No. 638,029, dated November 28, 1899.

Application filed May 8, 1899. Serial No. 716,004. (No model.)

To all whom it may concern:

Be it known that I, BARTON L. PECK, a citizen of the United States, residing at Detroit, in the county of Wayne and State of Michigan, have invented certain new and useful Improvements in Motor-Vehicles, of which the following is a specification, reference being had therein to the accompanying drawings.

My invention relates to transmission-gears designed to be used on motor-vehicles.

It is the object of my invention to obtain a simple construction of gearing by means of which the speed of the vehicle is controlled by the operator, who also is enabled thereby to reverse the direction of movement and apply the brakes; and the invention consists in the peculiar construction, arrangement, and combination of parts, as hereinafter described and claimed.

20 In the drawings, Figure 1 is a diagram plan view of a portion of a motor-vehicle to which my transmission-gear is applied. Fig. 2 is an enlarged sectional plan view of the gearing. Fig. 3 is a vertical longitudinal section on line xx , Fig. 2. Fig. 4 is a detail view of the cam for operating the clutch.

My improved gearing is especially designed for motor-vehicles in which the engine or other motor is carried by the body of the vehicle, the latter being supported by springs upon the wheel or truck frame. With such constructions, the body having an independent vertical movement from the wheels, it is necessary to provide a more or less flexible connection between the drive-shaft and the driven wheels. This I have provided for in my gearing, which is constructed as follows:

40 A is a box or casing which is preferably secured at one side of the body of the vehicle adjacent to the motor, and which I have indicated in the drawings by dotted lines at C.

The construction of this motor is not essential; but I have indicated a gas-engine having the main or drive shaft D, which extends laterally through the walls of the casing A and is journaled in suitable bearings therein. Upon this shaft is fixedly secured within the casing the gear-wheel E, preferably near the inner edge of said casing. At the opposite 45 end of the shaft is loosely sleeved the gear-wheel F, which is preferably also journaled

in a bearing G in the outer wall of the casing, the end of the shaft D being stepped into said gear. The gear F is provided with an outwardly-extending stub-shaft H, to which 55 is secured bevel or other gear I, meshing with a corresponding gear J on a shaft K, journaled in the bearing L, secured to the casing and extending at substantially right angles to the shaft D. The shaft K is formed in two 60 sections a and b , which are coupled by a universal coupling to permit said sections to move out of exact alinement to compensate for the independent movement of the vehicle-body. This universal coupling I have shown 65 as comprising the two heads c d , secured, respectively, to the sections a and b , one of said heads being provided with the projecting pins e , which loosely engage with sockets f in the opposite head. The section b of the shaft 70 extends in proximity to the rear axle, being journaled in a suitable bearing, such as M, and connected by the bevel or other suitable gears M' and M^2 with said axle. Adjacent to the shaft D and parallel thereto are arranged 75 a series of stationary shafts. These I have shown in the drawings as consisting of the shafts N, O, and P, which are secured at their ends in bearings Q at opposite sides of the casing A. Upon each of these shafts is arranged adjacent to each other two sleeves, respectively, R S, R' S', and R² S². The sleeves R, R', and R² are provided with gear-wheels T, T', and T², which mesh directly or indirectly with the fixed gear-wheel E upon 80 the shaft D. The sleeves S, S', and S² are correspondingly provided with gear-wheels U, U', and U², meshing directly or indirectly with the gear-wheel F on the shaft D. The two groups of gear-wheels constitute differential gear-trains, the former moving with the gear-wheel E on the shaft D and the latter with the gear-wheel F thereon. Each pair 85 of sleeves, as well as the shaft D, is provided with a suitable clutch, respectively, V V' V² 90 V³, adapted when operated to couple the said sleeves together or to couple the gear-wheel F directly with the shaft D.

It will thus be seen that the gear-wheel F may be driven by the shaft D either directly 100 or through the medium of any coupled pair of gear-wheels arranged on the parallel shafts

N O P N², and the proportion and arrangement of the gears are such that each pair will drive the gear-wheel F differently from the others.

- 5 As shown in the drawings, the clutches comprise a series of disks *g*, feathered to one of the sleeves of the shaft, an inclosing casing *h*, secured to the opposite sleeve and provided with an intervening series of disks *i*, feathered 70 to said casing. Fulcrumed to this casing is the lever *j*, adapted to press said disks into frictional contact with each other, said lever being operated by a connection with the longitudinally-sliding sleeve *k*, which has suitable connections with the operating-lever on the vehicle.

With the construction as thus far described it will be readily understood that whenever motion is imparted to the shaft D all the gears 20 in the train meshing with the gear-wheel E will be driven, but the gears in the train corresponding to the gear-wheel F will remain stationary unless one of the clutches is operated. When one of these clutches, such as V, is 25 operated, motion will be imparted therethrough to the gear-wheel F and also to the other gears of the train. These other gears, however, run loosely upon their respective shafts as idlers, with the exception of the particular one through which the driving is effected. Thus when the clutch V is operated the gear F will be driven in the same direction and at the same speed as the shaft D. When the clutch V' is used, the gear F will 35 also be driven in the same direction, but at a slower speed. Again, when the clutch V² is operated the gear F will be driven in the same direction at a still slower speed. When the clutch V³ is operated, the direction of movement of the gear F will be reversed, and this is accomplished by placing an intermediate gear U³ between the gear-wheels U' U², which will reverse the direction of the latter.

The shafts N, O, and P are preferably hollow and are provided with a series of apertures *l*, while at the ends of said shafts are formed the chambers *m* in the bearings Q, which serve as oil-pockets, from which the lubricant is distributed through the hollow 50 shafts and apertures *l*. This arrangement enables me to perfectly lubricate the bearings for the sleeves upon said shafts, and as the latter completely covers the shaft dust and dirt will be effectually excluded from the 55 bearings.

The clutches on the different shafts are preferably staggered in relation to each other, so as to facilitate their connections with the operating-levers. The clutch V is also preferably located within the gear-wheel F, which is recessed to receive the friction-disks *g i*.

The levers for operating the clutches may be arranged in any suitable way; but in the drawings I have shown two levers *p* and *p'*, secured, respectively, to the rock-shafts *q* and *q'*, journaled in the casing. Mounted upon

these rock-shafts are heads *r* and *r'*, which are provided with cam-slots with which the ends of the levers *t*, *t'*, *t²*, and *t³* engage. These levers correspond in number to the 70 clutches, and they are fulcrumed in suitable standards, such as *u* and *u'*, while their opposite ends are bifurcated to engage, respectively, with the sleeves *k* of the different clutches.

v is a rock-arm loosely pivoted on the shaft *q'* and carrying at its free end a brake-shoe adapted to engage with the periphery of the casing of the clutch V³.

w is a rod pivotally connected at one end 80 to the arm *v* and at its opposite end connected to an eccentric on the shaft *q*.

The parts above described are so arranged and the cam-slots in the heads *r* and *r'* are so formed that by throwing the levers *p* and *p'* 85 to various points any one of the clutches may be operated or all may be released, while by operating the lever *p* in the reverse direction the brake may be applied. Moreover, the arrangement is such that by throwing the 90 handles of either of said levers *p* and *p'* forward—that is, from their central position in the direction of forward movement of the vehicle—the proper clutches will be operated to drive the vehicle forward, while by throwing said levers backward one of them (the lever *p*) will reverse the direction of the vehicle and the other one (the lever *p'*) will apply the brake.

What I claim as my invention is—

1. A transmission-gear comprising a drive-shaft a fixed and a loose gear-wheel thereon, a parallel stationary shaft having a central longitudinal oil-passage and distributing-apertures at different points connecting with 105 said central passage, two gear-wheels having elongated hubs or sleeves journaled upon said stationary shaft and meshing, respectively, with said fixed and loose gear-wheels on the drive-shaft, and a clutch for coupling 110 together said gears on said stationary shaft.

2. A transmission-gear comprising a frame, a drive-shaft extending thereacross, a gear-wheel having a stub-axle journaled in said frame in line with said drive-shaft, said gear-wheel being recessed upon one side and having a central socket in which the end of said drive-shaft is journaled, and a friction-clutch 115 for coupling said gear-wheel to said shaft, located in said recess.

3. A transmission-gear comprising a drive-shaft and a plurality of stationary shafts, parallel thereto, a fixed and a loose gear-wheel on said drive-shaft, a pair of gear-wheels journaled on each of said stationary 125 shafts in line respectively with said fixed and loose gear-wheels on said drive-shaft and constituting therewith two differential gear-trains, and a clutch for coupling each pair of gear-wheels to each other.

4. A transmission-gear comprising a drive-shaft, a plurality of stationary shafts parallel

thereto, a fixed and a loose gear-wheel on said drive-shaft, a pair of wheels journaled on each of said stationary shafts in line respectively with said fixed and loose gear-wheels on the drive-shaft, and constituting therewith two differential gear-trains, a clutch for coupling each pair of gear-wheels to each other, and an intermediate gear-wheel in one train

between the corresponding gear of two pairs for the purpose described. 10

In testimony whereof I affix my signature in presence of two witnesses.

BARTON L. PECK.
